J. E. FITZGERALD

CONTAINER

Filed July 25, 1927

UNITED STATES PATENT OFFICE.

JAMES E. FITZGERALD, OF YOUNGSTOWN, OHIO, ASSIGNOR TO THE NILES STEEL PRODUCTS COMPANY, OF NILES, OHIO, A CORPORATION OF OHIO.

CONTAINER.

Application filed July 25, 1927. Serial No. 208,095.

This invention relates to a sheet metal container and is an improvement over the construction disclosed in my prior application Serial No. 130,215, filed August 19, 5 1926.

In said prior application, I have provided a container wherein the cover is secured in place by what may be termed a "ring seal". The body of the container has a bead at the 10 top and the cover fits down into the top of the container and has a flange overlying the bead, there being an intervening gasket. The cover is then secured in place and sealed against leakage by a sealing ring having 15 separable ends, this ring having an inwardly extending flange which overlies the flange of the cover and having a continuous down-turned flange which, while downward pressure is applied to compress the gasket, is 20 crimped inwardly at intervals, bending spaced portions inwardly at substantially right angles beneath the bead and leaving intervening uncrimped portions joining the crimped portions.

25 When it is desired to open the container, the ends of the sealing ring are separated and then the sealing ring is stripped off. The cover can then be lifted off and the contents of the container removed.

30 This container has proved to be satisfactory in most respects but it has the disadvantage that after the sealing ring is removed there is no means for effectively fastening the cover in place, this being of importance when only a portion of the 35 contents of the container has been removed when the container is first opened and when it is desired to protect the remaining contents of the container against the entrance 40 of foreign matter.

The present invention contemplates an addition to the structure of my prior application which makes it possible to close and at least partially seal the container head after 45 the sealing ring has been stripped off and the container once opened.

The invention may be briefly summarized as consisting in certain novel combinations and arrangements of parts which will be described in the specification and set forth in the appended claims.

Referring to the drawings, Fig. 1 is a side elevation of a container embodying my invention; Fig. 2 is an enlarged fragmentary

sectional view substantially along the line 55 2-2 of Fig. 1; Fig. 3 is a similar view substantially along the line 3-3 of Fig. 1 and Fig. 6; Fig. 4 is a similar view substantially along the line 4-4 of Fig. 6; Fig. 5 is a similar view substantially along the line 60 5-5 of Fig. 1; Fig. 6 is a top plan view of the container; Fig. 7 is an inverted view of the cover proper showing the tongues which are added in accordance with the present invention; Fig. 8 is a fragmentary 65 perspective view of a portion of the cover; and Fig. 9 is a view showing the top portion of the container, illustrating how the cover may be fastened in place to form a partial seal when the sealing ring has been 70 stripped off and the container once opened.

The container 10 is provided at the top with a bead 11. The cover 12 has a recessed portion which fits down inside the bead and it has a laterally projecting horizontal 75 flange 13 which is adapted to project over the bead, there being provided between this flange of the cover and the bead a gasket 14.

When the container is filled and is ready for shipment, the cover is placed in position 80 and it is then secured in place and sealed against leakage by a sealing ring 15 which, by means of a closing tool, is crimped inwardly under the bead 11, the cover and sealing ring being pressed downward so as 85 to tightly compress the gasket 14 in the closing operation. This sealing ring has an inwardly extending flange which overlies the flange 13 of the cover, and it has a continuous downwardly extending flange which in 90 the closing operation is crimped inwardly at intervals beneath the bead, as shown at 15^a, leaving intervening uncrimped portions, shown at 15^b. When the portions 15^a are 95 crimped inwardly, they extend well under the bead to the body portion of the container, being bent inwardly at substantially right angles, and the uncrimped portions are at the same time slightly curved and drawn inwardly, particularly where they join the 100 crimped portions, forming the equivalent of arches or trusses which join the crimped portions, thus adding considerable strength to the top portion of the container.

The sealing ring has separable ends normally fastened together by spot welding, soldering, or otherwise, and when it is desired to open the container, the ends of the 105

ring are separated, after which it can be readily stripped off the container, allowing the cover to be removed.

The container as so far described is substantially that constituting the subject matter of my prior application.

It is frequently the case that when this container is first opened, only a portion of the contents is removed, in which event it is desirable that the container be effectively closed against the entrance of dirt and other foreign matter. However, when once the sealing ring has been stripped off, prior to the present invention there was no way to effectively fasten the cover in place, and to overcome this objection the present invention has been provided. This consists in the provision of a series of tongues 16 which extend down from the edge of the flange 13 and at right angles thereto. A sufficient number of these tongues will be provided to answer the requirements, but in this instance three of them are shown, these being preferably equally spaced. When the cover is applied, these tongues extend down just outside of the bead 11 and the sealing ring is made just large enough so that the outer downturned flange thereof will fit down tightly over these tongues. It is not material whether in the closing operation all of the tongues 16 are bent inwardly under the bead 11 but generally one of the tongues is bent inwardly as indicated in Fig. 4, in which event the other two occur opposite or in line with the uncrimped portions, as indicated in Fig. 3.

In removing the cover, the sealing ring is stripped off in the usual manner and the cover can be then pried off, in which event the inwardly bent tongue 16 can act as a hinge to enable the cover to be swung back off the top of the container. Therefore, when one of the tongues is bent inwardly in the closing operation, the advantage just stated is attained. In some instances, two or all three of the tongues will, in the closing operation, be bent inwardly under the bead of the container, in which case the tongues assist in holding the cover in place and sealing it, but to remove the cover it is necessary to straighten out two of the tongues before the cover can be removed. This, however, has

no distinct disadvantage as the tongues can be straightened readily by a suitable tool.

When it is desired to restore the cover, it is placed in position in the usual manner, and while the cover is being pressed down so as to compress the gasket, the tongues will be bent inwardly by a suitable tool, such as a hammer in which event the cover will be held in place and will be wholly or partially sealed although, of course, not as effectively as originally.

It will be obvious that the number and spacing of the tongues may be varied as desired, and while I prefer, in the closing operation, to crimp under the bead spaced portions only of the downturned flange of the sealing ring, so far as the present improvements are concerned the entire flange might be crimped inwardly. I therefore do not desire to be confined to the precise details and arrangements shown, but aim in my claims to cover all modifications which do not involve a departure from the spirit and scope of the invention.

Having thus described my invention, I claim:

1. A container comprising a body having a bead at the top, a cover having a marginal portion adapted to project over the bead and having marginal tongues adapted to project down outside of the bead, and a sealing ring adapted to overlie the marginal portion of the cover and to project down around the bead and the tongues and to be bent inwardly under the bead.

2. A container having a bead at the top, a cover having a depressed portion adapted to be inserted inside the top of the container and having a marginal flange projecting over the bead, there being a gasket between said flange and the bead and said flange having at its margin a plurality of spaced tongues which project down alongside and beneath the bead, and a sealing ring having a horizontal flange overlying the flange of the cover and having a downturned flange fitted around the bead and said tongues and adapted to be bent inwardly beneath the bead.

In testimony whereof, I hereunto affix my signature.

JAMES E. FITZGERALD.
